2,283,460

PISTON

Charles M. Pumphrey, Wharton, Tex.

Application March 10, 1941, Serial No. 382,645

2 Claims. (CL. 309—4)

This invention relates to pump pistons, and particularly to pump pistons designed primarily for use in pumping mud, or similar semi-liquid materials.

An important object of the invention is to provide a piston of this character embodying piston packing rings or inserts constructed of flexible wear-resisting material, and adapted to insure a close fit between the piston and its cylinder wall, during the working stroke of the piston, and move away from the cylinder wall during the return stroke of the piston, thereby clearing the wall of the cylinder of material which would cut or otherwise damage the piston or cylinder wall.

Another object of the invention is to provide a packing ring which will flex with the movements of the piston on which the packing ring is mounted, insuring a close fit between the piston and its cylinder, and eliminating any possibility of the packing ring bending rearwardly on the power stroke.

A still further object of the invention is to provide means for permitting horizontal and vertical play of the piston within its cylinder, without effecting the seal between the piston and cylinder.

Another important object of the invention is to provide a flexible piston packing having a flexible steel bracing member embedded therein, the bracing member being designed to permit flexibility of the packing and at the same time lend rigidity to the packing, increasing the wear qualities of the packing.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a longitudinal sectional view through a piston constructed in accordance with the invention, and illustrating the piston as moving in a cylinder.

Figure 2 is a sectional view taken on line 2—2 of Figure 1.

Referring to the drawing in detail, the reference character 5 designates the piston rod, which is formed with an enlargement 6 disposed in spaced relation with the free end of the rod, the

enlargement 6 providing an abutment for one end of the piston.

The piston comprises a body portion 7 which is of a diameter appreciably less than the diameter of the cylinder in which it moves, providing a wide space between the piston and cylinder wall.

The ends of the body portion are tapered inwardly, providing inclined surfaces or seats for the packing rings 8, mounted at each end of the body portion.

As clearly shown by Figure 1 of the drawing, the inclined end walls of the body portion, have their outer ends spaced from the periphery of the body portion, providing substantially straight surfaces 9 at the ends of the body portion.

At each end of the body portion 7, is a packing ring 10 constructed of suitable wear-resisting material, preferably rubber. These packing rings are molded around flexible steel disk-like members 11 formed with rolled outer ends 12, to reduce wear at the ends of the body portion, of the packing rings, to the minimum. Openings are formed in the flexible steel members, and when the wear-resisting material is molded around the members, the flexible wear-resisting material will find its way into the openings, securing the members in position.

The outer or cylinder-engaging edges of the packing ring 10, are of a construction to permit of free sliding movements of the packing rings, but at the same time eliminate any possibility of the packing rings folding rearwardly on the power stroke of the piston.

As shown, the cylinder-engaging surfaces of the packing rings are enlarged and curved, as at 13.

The packings rings 10, are held in position on the body portion 7, by the disks 14 which are shaped to conform to the recessed ends of the body portion. The disks 14 are of diameters less than the diameter of the piston, providing ample space at the ends of the piston to allow the rings 10 to flex freely. One end of the piston rod 5 is threaded to receive the nuts 15, which, when properly positioned, direct pressure to the disks 13, clamping the packing rings onto the body portion.

From the foregoing it will be seen that due to the construction shown and described, a packing ring on the pumping stroke will move rearwardly against the straight surface 9 of the body portion 7, insuring a close fit between the packing ring and cylinder wall. The packing ring at the opposite end will of course move away from the straight surface 9 adjacent thereto,

permitting of free flexing of the packing ring to permit foreign matter which may collect between the ring and cylinder wall, to fall away from the cylinder wall. Upon the return movement of the piston, the rings will move in the opposite directions providing a close fit between the ring and cylinder wall, while the ring at the opposite end of the body portion moves away from the cylinder wall.

What is claimed is:

1. In a pump for pumping semi-solid material, a pump cylinder, a piston comprising a body portion having inclined recessed end walls, terminating in substantially straight flat surfaces and providing shoulders adjacent to the periphery of the piston, flexible packing rings fitted over the inclined end walls, the outer edges of the packing rings extending an appreciable distance beyond the periphery of the piston, a steel disk-like member embedded in said packing rings and adapted to hold the packing rings substantially rigid, against the wall of the cylinder, and disks for securing the packing rings to the ends of the piston.

2. In a pump for pumping semi-solid material, a pump cylinder, a piston comprising a body portion having inclined recessed end walls, terminating in substantially straight flat surfaces providing shoulders adjacent to the periphery of the piston, flexible packing rings fitted over the inclined end walls, the outer edges thereof extending an appreciable distance beyond the periphery of the piston, portions of the packing rings 5 adjacent to the free edges thereof being substantially thick, a disk-like steel member embedded in each packing ring, the outer edges of the disk-like steel members terminating at points where the thickened portions of the packing rings 10 rings merge into the main portions of the packing rings, the thickened portions of the packing rings adapted to rest against the shoulders on one stroke of the piston, and means for securing the packing rings to the inclined end walls of the piston.

CHARLES M. PUMPHREY.
